US0D1035668S

(12) **United States Design Patent** (10) Patent No.: **US D1,035,668 S**
(45) Date of Patent: ** Jul. 16, 2024

(54) **TABLET CASE**

(71) Applicant: **Shenzhen Zhongbo Dingsheng Technology Co., Ltd.**, Shenzhen (CN)

(72) Inventor: **Zhaohong Xu**, Shenzhen (CN)

(**) Term: **15 Years**

(21) Appl. No.: **35/518,949**

(22) Filed: **Oct. 20, 2023**

(80) **Hague Agreement Data**

Int. Filing Date: **Oct. 20, 2023**

Int. Reg. No.: **DM/232764**

Int. Reg. Date: **Oct. 20, 2023**

Int. Reg. Pub. Date: **Nov. 10, 2023**

(51) **LOC (14) Cl.** **14-02**
(52) **U.S. Cl.**

USPC **D14/440**

(58) **Field of Classification Search**

USPC D14/440, 315, 318, 324, 328, 341, 344, D14/345, 389, 392, 444, 445, 250, D19/26, 62; D3/247, 290, 299, 206
CPC A45C 2011/003; A45C 2200/15; A45F 2200/0516; A45F 2200/525; G06F 1/1628; G06F 1/1632; G06F 1/1669; G06F 2200/1633; H04B 1/3888; H04M 1/185

Primary Examiner — Daniel J Domino

Assistant Examiner — Samina Vieth

(57) **CLAIM**

The ornamental design for a tablet case, as shown and described.

DESCRIPTION

1. Tablet case

1.1 : Perspective

1.2 : Perspective

1.3 : Front

1.4 : Back

1.5 : Left

1.6 : Right

1.7 : Top

1.8 : Bottom

The parts shown by means of broken lines in the reproductions are not part of the claimed design.

1 Claim, 8 Drawing Sheets
